OPEN-WORK PANELS

FILED Nov. 13, 1885

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 17,132, dated February 22, 1887.

Application filed November 13, 1885. Serial No. 182,764. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

Upon the face of the panel appear sinuous configurations, as A B, placed in juxtaposition. At each bend of said configurations is a concave surface, C, inclined inwardly through the panel. Extending through the panel and at regular intervals apart are hexagonal openings, having two straight and opposite parallel sides, D E, which sides are the inner edges of the inclined surfaces C, and four inwardly-

convex sides, F G H I. The outer curved boundaries, J, of the surfaces C meet the sides F G H I, and the said sides and boundaries being repeated constitute the outline of the sinuous configurations, as A B. At K are openings extending through the panel.

I claim—

The design for an open-work panel, substantially as herein shown and described, which consists in the sinuous configurations A B, the inclined surfaces C, apertures K, and the hexagonal openings D E F G H I.

FREDERICK MANKEY.
